UNITED STATES PATENT OFFICE.

EPHRAIM P. GRIGNON, OF APPLETON, WISCONSIN.

FOLDABLE TABLE.

Application filed May 28, 1923. Serial No. 641,955.

To all whom it may concern:

Be it known that I, EPHRAIM P. GRIGNON, a citizen of the United States, and resident of Appleton, in the county of Outagamie 5 and State of Wisconsin, have invented new and useful Improvements in Foldable Tables, of which the following is a description, reference being had to the accompanying drawings, which are a part of this specification.

This invention relates to foldable tables, and has for one of its objects to provide a table of this character which is especially, although not solely, adapted for carrying in 15 automobiles.

A further object of the invention is to provide a table having a top composed of a plurality of relatively narrow slats suitably connected together, whereby the table 20 may be reduced to contracted form, occupying a minimum amount of space.

A further object of the invention is to provide a table having a top of the character just described and provided with suitable supporting and bracing members whereby it may be rigidly maintained in its extended position.

A still further object of the invention is to provide a special hinge construction 30 whereby the table top, legs and supporting members may be readily and pivotally connected to the end that they may be quickly and easily collapsed for folding the table.

A still further object of the invention is to provide a table of the class described 35 which will be simple in construction, comparatively inexpensive to manufacture and more efficient in use than those which have been heretofore proposed.

Referring to the accompanying drawings 40 in which like reference characters designate like parts in all the views;

Figure 1 is a perspective view of a table constructed in accordance with the present 45 invention shown in its open or extended position;

Fig. 2 is a transverse sectional view, through the top portion of the table, taken approximately on the plane indicated by the 50 line 2—2 of Fig. 1, looking in the direction of the arrows;

Fig. 3 is an inverted plan view, partly in 55 section, of one corner of the table in extended position, one of the supporting arms being partly in collapsed position;

Fig. 4 is an end elevational view of a por-

tion of one corner of the table in inverted position, showing the top, a supporting member, a leg and one of the end braces, as well as the hinge construction whereby the 60 parts are pivotally secured together;

Fig. 5 is an enlarged detail cross sectional view of the brace member shown in Fig. 4, taken approximately on the plane indicated by the line 5—5 of the said figure; 65

Fig. 6 is an enlarged detail sectional view, through a portion of the table top illustrating the manner of connecting the individual slats of the said top together;

Fig. 7 is a view similar to Fig. 6, showing 70 a slightly modified method of connecting the slats together;

Fig. 8 is a fragmentary detail perspective view of the hinge construction above mentioned; and, 75

Fig. 9 is a diagrammatic view illustrating the way in which the table may be rolled up when collapsed, in order to occupy the minimum amount of space.

In the said drawings the numeral 11 indicates generally the top of the table which, as will be clear from Figs. 1, 2 and 3, is composed of a main section 12, formed of a plurality of slats or bars 13, and the end members 14 which are preferably, although not necessarily of somewhat thicker material than are the slats 13. The said slats 13 may be hinged together in any suitable manner, as for example by means of the canvas or other fabric strips 15, extending 80 across the under faces of the slats 13, between the two end pieces 14, as will be readily understood from Figs. 2 and 3. 85

The said canvas strips, as clearly indicated in Figs. 3 and 6 may be secured to 90 each individual slat by means of the split tacks or brads 16, or as illustrated in the modified construction shown in Fig. 7, by means of the rivets 17 extending entirely through the slats 13 with their lower ends 100 bent over the strip as indicated in the said figure.

Each end of each of the end members 14 has pivotally secured to it by the hinge member 18, to be presently described, a supporting leg 19, and the said hinge member 18 also pivotally secures to the said legs and top members 14 the side supporting members 20 and 21, which extend transversely beneath the ends of the slats 13 and 105 serve to form a rigid support therefor. The said members 20 and 21, as will be clear 110

- from the drawings, are respectively pivotally secured at opposite ends of the table and are preferably of substantially the form shown, whereby they may be moved into vertical alignment when in the extended position of the parts and in conjunction with the braces to be presently described, to adequately support the slat members 13 of the top 11.
- 10 Each of the supporting members 20 has pivotally secured to it, as by the screws or other fastenings 22, a pair of brace members 23, which preferably take the form of flat metallic straps. The said members 23 are provided at the ends opposite to the pivots 22 with hook portions 24 adapted to engage pins or screws 25 carried by the legs 19 of the table, and the said brace members are also provided intermediate their ends with notches or recesses 26, adapted to receive the pins or screws 27 carried by the companion supporting members, 21, as will be clear from Fig. 2. These brace members 23, when in their extended positions serve to not only brace the legs 19 of the table in a transverse direction, but they also serve to lock the hinged supporting members 20 and 21 in their operative positions and prevent the undesired collapse of the table.
- 15 In order to brace the leg members 19 in the direction of right angles to the braces 23, there is provided the two-part brace members 30, each comprising a pair of metal strips 31 and 32, which overlap one another and are pivotally secured together as at 33. The end of the strip 31 is pivotally secured to the member 14 as by the bracket 34, while the free end of the strip 32 is pivotally secured to the leg 19 as by the bolt or pivot 35.
- 20 The member 31, as best shown in Fig. 5, is provided with a projection or boss 36, which is adapted to engage in a recess or aperture 37 with which the companion member 32 is provided, thereby affording a means for locking the two members in their extended positions while at the same time, due to the resilience of the parts, permitting of the said locking projection being readily disengaged from its recess or aperture 37 when it is desired to fold the table. The members 31 may be bent outwardly as indicated at 38 to facilitate the straightening or breaking of the brace members 30, as will be readily understood.
- 25 As was above mentioned, a peculiar form of hinge is preferably employed in connecting the legs 19 and supporting members 20 and 21 to the table top. This hinge construction, as is best shown in Fig. 8, preferably comprises a body member 40 which is bent to provide two angularly disposed portions, 41 and 42, to which are respectively secured as by the hinge pins 43 and 44, the leaves 45 and 46. As will be clear from the said figure the leaf 45 is secured to

the leg 19 by screws or other fastenings 47, while the portion 41 of the body member 40 is secured to the top members 14 by the screws 48, and the leaf 46 is secured to the supporting members 20 or 21 by the screws 70 or fastenings 49. It thus results that the three table members, viz, the top, the leg and the supporting members, are hingedly secured together in the required planes at right angles to each other by a single hinge 75 construction which effectively secures the parts together while at the same time permitting of the ready folding of the parts when it is desired to collapse the table.

Assuming the table to be extended, as illustrated in Fig. 1, should it be desired to collapse the same, the brace members 23 are first disengaged from the pins or screws 25 of the legs and are swung inwardly to occupy positions adjacent the inner face of 85 the supporting member 20 to which they are secured. This movement of the bracing members 23 will, of course, disengage the pins or screws 27, carried by the supporting members 21 from the recesses 26 of the said 90 bracing members, and will permit the said supporting members to be swung inwardly about the vertical pivot pins 44 of the hinge members 40 to occupy positions parallel to the members 14.

The two-part bracing members 30 may then be broken, permitting the legs 19 to be folded up beneath the members 14 whereupon the entire table may be rolled up substantially as illustrated in Fig. 9 and secured 100 by suitable binding cords or strips in its collapsed position. The rolling of the table is permitted by the construction of the table top, as will be readily understood.

It will thus be seen that this invention 105 provides a table which when in its extended position is braced in all directions, and is extremely rigid, while at the same time it may be readily collapsed and folded to occupy a minimum amount of space. This is extremely desirable in tables which are to be carried and used in motor vehicles, especially when of the pleasure type where space is more or less at a premium.

While one form of the invention has been 110 illustrated and described herein it is obvious that those skilled in the art may vary the details of construction as well as the arrangement of parts without departing from the spirit of the invention, and therefore it is not wished to be limited to the above disclosure except as may be required by the accompanying claims.

What is claimed is:

1. In a foldable table a top adapted to be rolled up; legs hingedly secured to said top; and side rail members hingedly secured to each of said legs for movement in a horizontal plane, adapted in the open position of the table to occupy positions in super- 125

posed vertical pairs and to support said top in its extended position.

2. In a collapsible table a top comprising a plurality of parallel disposed slats hingedly secured together; legs hingedly secured to said top adapted to fold in positions parallel and adjacent to said slats; and a supporting member hingedly carried by each of said legs for movement in a horizontal plane whereby they may be folded to occupy positions parallel to said slats and opened to extend transversely of said slats and to support the same, each of said supporting members being of a length approximately equal to the length of the table top whereby they may be positioned in superposed vertical pairs when the table is in open position.

3. In a collapsible table, a top adapted to be rolled up, legs pivotally secured to said top; a side rail member pivotally secured to each of said legs for movement in a horizontal plane, pairs of said members being arranged to assume vertically aligned positions to support the top when the table is extended; braces for maintaining said legs in open position; and means for locking said pairs of members in their vertically aligned supporting positions.

4. In a collapsible table, a top adapted to be rolled up; legs pivotally secured to said top; members pivotally secured to each of said legs, pairs of which are adapted to assume vertically aligned co-acting positions to support said top when it is extended; braces pivotally secured to said top and legs for maintaining said legs in an open position; and means pivotally carried by certain of said supporting members and adapted to readily detachably engage said legs, for locking said supporting members in their vertically aligned supporting position.

5. A collapsible table comprising a top composed of a plurality of parallel disposed

slats having secured to one of their faces strips of flexible material; legs pivotally secured to said top, adapted to be swung from an open position at right angles thereto, to a folded position parallel and adjacent said slats; and a supporting member pivotally secured to each leg, adapted when folded to occupy a position parallel to said slats, and when open to extend in vertically aligned pairs transversely beneath slats to support the same.

6. A collapsible table comprising a top composed of a plurality of parallel disposed slats having secured to one of their faces strips of flexible material; legs pivotally secured to said top, adapted to be swung from an open position at right angles thereto, to a folded position parallel and adjacent said slats; a supporting member pivotally secured to each leg, adapted when folded to occupy a position parallel to said slats, and when open to extend in vertically aligned pairs transversely beneath slats to support the same; means for locking and bracing said legs in their open position; and additional means for locking and bracing said supporting members in their vertically aligned open position.

7. In a table of the class described, a flexible top; a plurality of legs each provided with a pin, pivotally carried by said top; a supporting member pivotally secured to each of said legs for swinging movements in a substantially horizontal plane beneath said top; locking projections carried by some of said supporting members; and bracing and locking members pivotally carried by others of said supporting members, adapted to engage the pins carried by said legs and provided with recesses for engagement with said projections.

In testimony whereof, I affix my signature.

EPHRAIM P. GRIGNON.
